CLAIM

The ornamental design for a wear and adjustment indicator for vehicle brakes system, substantially as shown and described.

DESCRIPTION

FIG. 1 is a front view of a wear and adjustment indicator for vehicle brakes system showing my new design; FIG. 2 is a rear view of the decals used to form the design of FIG. 1; and FIG. 3 is a side view thereof.

The dotted line portion shown in FIG. 1 is disclosed for illustrative purposes only and form no part of the claimed design.
